UNITED STATES PATENT OFFICE.

MAX J. PALM, JR., OF CINCINNATI, OHIO, ASSIGNOR TO THE PALM BROTHERS DE-CALCOMANIA COMPANY, OF NORWOOD, OHIO, A CORPORATION OF OHIO.

DESIGN FOR A PLATE OR SIMILAR ARTICLE.

Application filed March 2, 1926. Serial No. 16,740. Term of patent 7 years.

To all whom it may concern:

Be it known that I, MAX J. PALM, Jr., a citizen of the United States of America, and a resident of Cincinnati, in the county of Hamilton and State of Ohio, have invented a new, original, and ornamental Design for a Plate or Similar Article, of which the following is a specification, reference being had to the accompanying drawing, forming part thereof.

The figure is a plan view of a plate or similar article showing my new design.

The plate is partially broken away at the right hand margin.

I claim:

The ornamental design for a plate or similar article, as shown and described.

MAX J. PALM, Jr.
